UNITED STATES PATENT OFFICE.

WILLARD T. MEAD, OF BUFFALO, NEW YORK.

PHOTOGRAPHIC-PRINTING MACHINE.

SPECIFICATION forming part of Letters Patent No. 783,639, dated February 28, 1905.

Application filed December 10, 1904. Serial No. 236,261.

To all whom it may concern:

Be it known that I, WILLARD T. MEAD, a citizen of the United States, residing at Buffalo, in the county of Erie and State of New York, have invented a new and useful Improvement 5 in Photographic-Printing Machines, of which the following is a specification.

This invention relates to photographic-printing machines of that kind comprising a 10 rotatable drum having a transparent peripheral wall and an enveloping curtain, between which the sensitized print paper or sheet and tracing or transparent original are introduced and subjected for a period of time to the action 15 of light within the drum to produce the print.

The invention is especially directed to machines for making blue-prints from tracings, but is not limited to such use.

20 The primary object of the invention is to provide an efficient practical photographic-printing machine of simple and inexpensive construction which can be fed or charged with rapidity and ease and discharged with 25 equal facility.

In the accompanying drawings, consisting of two sheets, Figure 1 is a side elevation of a photographic-printing machine embodying the invention. Fig. 2 is a transverse sectional elevation thereof. Fig. 3 is a longitudinal sectional elevation thereof. Fig. 4 is a side elevation of a modified construction.

Like letters of reference refer to like parts in the several figures.

30 A represents a stationary frame, which may be of any suitable form and construction, that shown consisting of connected sides having upright bearing extensions *a* for the rotatable drum and forwardly-projecting arms or extensions *a'*.

B represents the drum or cylinder, which preferably consists of two circular skeleton ends or heads *b*, which support and are connected by segmental cylindrical plates *c* of 45 glass or other suitable transparent material. The heads of the drum are connected between the glass plates by bars or strips *c'*, which constitute supports for the longitudinal edges of the glass plates. A drum having a continuous 50 cylindrical glass wall could be em-

ployed; but such construction is more expensive than that described, which is strong and desirable for ordinary work where excessively large prints are not required. A cylindrical drum is preferred; but a polygonal 55 drum could be used. The drum is mounted to rotate about a horizontal axis in any suitable manner. For instance, it is supported on fixed journals *d*, projecting inwardly from the bearing extensions *a* of the stationary frame, 60 and it is turned by suitable means, the ends of the drum being provided with circular hand - rails *e* for this purpose. Any other means for turning the drum can be used.

F represents lamps which are located with- 65 in the drum and furnish the light for printing. The electric lamps shown in the drawings are carried by a supporting bar or frame *f*, secured to the inner ends of the stationary journals for the drum, and they are supplied 70 with current by wires entering the drum through one of its journals or in any other known way. One or more lamps are employed, as may be found necessary.

G represents a curtain or apron, of thin flexible material, which is attached at one end to and is wound upon a roller *H*, arranged parallel to the drum, and is attached at its other or free end at *h* to the cylindrical wall of the drum *B*. The curtain-roller *H* is journaled 80 in fixed relation to the drum in suitable bearings *h'* on the frame *A* and is provided with means for revolving it in a direction to wind the curtain thereon. A spring-operated roller, such as the well-known window-shade roller, 85 can be used and is shown in Figs. 1 and 3, or the roller can be revolved to wind up the curtain by other means, such as a weight-motor *H'*. (Shown in Fig. 4.) When the drum *B* is turned forwardly, as indicated by the arrows, Figs. 1 and 3, the curtain *G* is unwound from its roller and wrapped around the drum, the spring or weight for the curtain-roller being thus wound up, and when the drum is turned backwardly the roller *H* automatically 90 rewinds the curtain thereon. The automatically-winding roller *H* always exerts a sufficient pull on the curtain to draw it taut around the drum, and thereby hold the tracings and print-paper securely against the transparent 100

wall of the drum and prevent the displacement of the same.

In the machine shown in Figs. 1 to 3 the curtain-roller is journaled in the forwardly-projecting arms a' of the frame, and the curtain extends therefrom in a substantially horizontal direction to the drum, passing over a guide and supporting roller I , which holds the curtain up against the cylindrical wall of the drum. The guide-roller at all times holds the curtain against the peripheral face of the drum, and while the curtain-roller itself could be located at the place occupied by the guide-roller and the latter dispensed with, as illustrated in Fig. 4, in which H^2 represents the curtain-roller, such arrangement is not so desirable, because the curtain-roll decreases in diameter as the curtain is unwound therefrom and the curtain may not at all times be held firmly against the drum. The guide-roller I is preferably pressed yieldingly against the drum by springs J beneath its journals, so as to hold the curtain tightly against the drum and prevent injury to the latter in case a hard object should be carried between the guide-roller and the drum by the curtain. A horizontal feed-board K , supported by the frame-arms a' in front of the curtain-roller H , is preferably employed, which, together with the horizontal portion of the curtain, forms a horizontal feed-table on which to place the tracings and print-paper when feeding the machine.

The drum can be held against backward rotation by the pull of the curtain, by a ratchet L and pawl L' , Fig. 1, or by any other device.

In operation the tracings and print-paper are placed in proper relation on the horizontal feed-table and the drum B rotated forwardly. As the drum and curtain G move in the same direction the tracings and print-paper will be gripped and carried in between the drum and curtain and firmly held by the latter against the drum. A single large tracing and print or several small ones can be fed into the machine to rest on each glass plate of the drum. When the drum is charged, the lamps F are lighted and the drum allowed to stand stationary until the printing is effected, after which the pawl L' is tripped and drum turned in the reverse direction or backwardly. The curtain-roller H rewinds the curtain G thereon, and the tracings and prints are discharged onto the feed-table.

As the feed-table, curtain, and drum are horizontal, the machine can be readily charged with a number of small tracings and print-papers of various sizes without danger of any of them being displaced, and thus spoiled. The machine is therefore much easier to operate

and more reliable than if a vertical cylinder and curtain were employed.

I claim as my invention—

1. The combination of a rotatable drum having a transparent peripheral portion, a source of light within the drum, a curtain attached at one end to said drum, and a roller to which the other end of said curtain is attached, and which is rotated in fixed relation to the drum to wind said curtain thereon, substantially as set forth. 70

2. The combination of a rotatable drum having a transparent peripheral portion, a source of light within the drum, a roller journaled in fixed relation to the drum, a curtain attached to said drum and to said roller and which is unwound from said roller by the rotation of the drum in one direction, and means for revolving said roller to rewind the curtain thereon when the drum is rotated in the opposite direction, substantially as set forth. 75

3. The combination of a rotatable drum having a transparent peripheral portion, a source of light within the drum, a curtain attached at one end to the drum and adapted to envelop the drum when the latter is rotated in one direction, a guide-roller over which the curtain passes, and means for maintaining the curtain taut at all times, substantially as set forth. 85

4. The combination of a rotatable drum having a transparent peripheral portion, a source of light within the drum, a roller journaled in fixed relation to the drum, a curtain attached to said roller and to the drum, means for winding the curtain on the roller, and a roller which presses the curtain against the periphery of the drum, substantially as set forth. 90

5. The combination of a horizontal rotatable drum having a transparent peripheral portion, a source of light within the drum, a horizontal feed-board, a roller journaled adjacent to said feed-board, and a curtain attached to said roller and extending in a substantially horizontal direction toward and attached to the drum, substantially as set forth. 100

6. The combination of a horizontal rotatable drum having a transparent peripheral portion, a source of light within the drum, a horizontal roller journaled in fixed relation in front of the drum, a curtain attached to said roller and extending in a substantially horizontal direction toward and attached to the drum, and a roller for holding the curtain against the periphery of the drum, substantially as set forth. 110

Witness my hand this 7th day of December, 1904.

WILLARD T. MEAD.
